SIGNORS TO THE FELINS TYING MACHINE CO., OF MILWAUKEE, WISCONSIN

VEGETABLE WASHER

Application filed January 23, 1928. Serial No. 248,644.

This invention relates to a vegetable washer.

Objects of this invention are to provide a novel form of vegetable washer in which the 5 brushes are carried by the shafts and are so constructed that fixed bearings may be used for the shafts, although the brushes are adjustable for wear.

Further objects of this invention are to 10 provide a novel form of vegetable washing machine in which an improved scrubbing action is secured, in which a plurality of cylindrical brushes are carried by each shaft, and in which each of the brushes is individually 15 adjustable.

Further objects are to provide a vegetable washing machine in which a small sized casing is all that is required, in which an upper and lower shield project outwardly from the 20 casing and thus do not increase the depth of the casing, in which means are provided for separating dislodged material, and keeping it from returning to the brushes.

Further objects are to provide a vegetable 25 washing machine in which a small amount of water is permitted to constantly reach the brushes while in operation, but which avoids the churning up of the entire volume of water employed by the machine.

An embodiment of the invention is shown 30 in the accompanying drawings in which:

Figure 1 is a front elevation partly in section of the machine with parts broken away;

Figure 2 is a sectional view on the line 35 2-2 of Figure 1.

Referring to the drawings, it will be seen that the machine comprises a main casing 1 provided with an open bottom portion 2. This casing is cut out or open at its front and 40 is provided with an upper shield plate 3 and a lower shield plate 4. These shield plates are inwardly turned, as is apparent from an inspection of the drawings and they terminate adjacent the cut out sides 5 of the machine.

A plurality of fixed bearings 6 and 7 support the horizontal shafts 8 and 9. These shafts are driven from a vertical shaft 10 by means of bevel gearing and such shaft may 50 be driven by reduction gearing from a small

electric motor 11 mounted on top of the casing.

The shafts 8 and 9 carry end spiders 12 which are provided with hook-like ends, each equipped with a set screw 13 for a purpose hereinafter to appear. These end spiders are spaced apart on the shafts and it is to be noted from Figures 1 and 2 that the shafts are further provided with intermediate spiders 14 which are not equipped with the 55 clamping set screws.

The hook-like portions of the spiders carry the trunnions or center stem 15 of a plurality of cylindrical brushes 16, as shown in Figure 2. The intermediate spiders 14 are not 60 clamped to these stems but merely receive them in their hook-like portions. It is apparent from an inspection of Figure 2 that the 65 bristles of the brushes intermesh when the brushes are assembled as shown.

It is to be noted particularly that an ordinary, simple type of brush may be employed whose trunnion or stem 15 consists merely of a pair of twisted wires of the usual construction.

It is to be noted that in the machine illustrated four of the cylindrical brushes are carried in each group and two groups of brushes are formed on each shaft. Obviously, any number of groups, or any number of brushes, 70 may be employed without departing from the spirit of this invention. It is preferable however to stagger the brushes of an upper and lower group, as shown in Figure 2, so that when one of the lower brushes is uppermost, 75 the adjacent upper brushes are positioned on opposite sides thereof. The brushes are so arranged that the upper group is approximately tangent to the lower group, as shown in Figure 1.

It is to be noted that the lower shield 4 is extended inwardly to provide an upwardly concave bottom shield 17. This bottom shield is provided with a plurality of narrow slots or openings 18 at its lowest point which allows water from the bottom of the casing 1 to pass upwardly to the brushes. The brushes rotate in the direction indicated by the arrows and sweep this water rapidly from the shield plate and carry it to the vegetables which are 80 85 90 95 100

being scrubbed by the machine. The vegetables are not struck by smooth, cylindrical surfaces of the brushes but are struck by brushes of different height, as measured from the center of their respective main shafts 8 and 9. Thus, a thorough washing is secured and one which is more effective than has heretofore been found possible with machine scrubbers or washers. Also, it is obvious that the casing may be made to contain water, if desired, or at all events, it is intended to receive water in its lower portion.

In using our improved washer, the casing is to be positioned within a tub or other receptacle having water therein, which will be passed upwardly into the casing after it enters through the slots or openings 18.

The motor 11 is started for imparting a rotating movement to the series of brushes mounted upon the shafts 8 and 9, the rotative movement of said brushes carrying the water upwardly from within the shield or guard plate 17. The vegetables which are preferably bunched for marketing are cleansed by inserting the vegetables between the brushes at the open side of the casing.

It will be apparent that after a certain period of constant use, the individual brushes through contact with the vegetables and each other will be worn off to a certain extent, and in order to adjust the surfaces of the brushes, the set screws 13 are loosened to permit rotative movement of each individual brush within the hook portions of the end spiders 12, so that a new scrubbing surface may be presented outwardly.

It will be seen that a very simple form of vegetable washer has been provided which is easy to construct, which does not require a thick or deep casing as no guard plates are positioned within the casing, and which is so constructed that there is no possible chance of spraying the operator by water thrown from the brushes.

Although the invention has been described in considerable detail, such description is intended as illustrative rather than limiting as the invention may be variously embodied and as the scope of such invention is to be determined as claimed.

We claim:

1. In a vegetable washing machine, the combination of a casing, a pair of parallel shafts projecting into said casing, fixed bearings supporting said shafts, and a plurality of brushes carried by each of said shafts and individually adjustable with respect to their corresponding shafts, each of said brushes being cylindrical with their axes paralleling said shafts.

2. In a vegetable washer, the combination of a casing, a pair of parallel shafts projecting into said casing, spiders carried by said shafts, a plurality of brushes associated with each shaft and having centrally disposed

stems carried by said spiders, and means for releasably locking said spiders and trunnions together, whereby said brushes may be rotated to compensate for wear and again locked to said spiders.

3. In a vegetable washer, the combination of a casing, a pair of parallel shafts projecting into said casing, spiders carried by said shafts, a plurality of cylindrical brushes associated with each shaft and having centrally disposed stems carried by said spiders, and means for releasably locking said spiders and trunnions together, whereby said brushes may be rotated to compensate for wear and again locked to said spiders, the brushes for each shaft having intermeshing bristles.

4. A vegetable washer comprising a casing having an open front and adapted to receive a supply of water in its lower portion, a pair of parallel horizontal shafts projecting into said casing, brushes carried by said shafts, and a shield located below the lower of said brushes and spaced from the bottom of said casing, said shield being concave upwardly and having a restricted passage in its lower portion for the passage of water, said shield continuing outwardly beyond the front face of said casing and being bent inwardly, the rear edge of said shield being spaced inwardly from the rear of said casing.

5. A vegetable washer comprising a casing having an open front and adapted to receive a supply of water in its lower portion, a pair of parallel horizontal shafts projecting into said casing, brushes carried by said shafts, and a shield located below the lower of said brushes and spaced from the bottom of said casing, said shield being concave upwardly and having a restricted passage in its lower portion for the passage of water, said shield continuing outwardly beyond the front face of said casing and being bent inwardly, the rear edge of said shield being spaced inwardly from the rear of said casing, and an upper downwardly projecting shield carried by and projecting beyond the front face of said casing.

6. A vegetable washer comprising a casing having an open front and adapted to receive a supply of water in its lower portion, a pair of parallel horizontal shafts projecting into said casing, brushes carried by said shafts, and a shield located below the lower of said brushes and spaced from the bottom of said casing, said shield being concave upwardly and having a restricted passage in its lower portion for the passage of water, said shield continuing outwardly beyond the front face of said casing and being bent inwardly, the rear edge of said shield being spaced inwardly from the rear of said casing, and an upper downwardly projecting shield carried by and projecting beyond the front face of said casing, said upper shield having an inwardly bent lower portion.

7. In a vegetable washing machine, the combination of a casing, a pair of parallel shafts projecting into the casing, and a plurality of brushes carried by each of said shafts and each brush being rotatably adjustable, independent of their corresponding shafts.

8. A vegetable washer comprising a casing having an opening in one wall thereof, rotatable brushes in said casing, a curved shield below said brushes with the major portion thereof arranged in the casing and formed with a plurality of openings, the outer edge of said shield being continued outwardly through the opening beyond the wall of the casing and curved upwardly and inwardly.

In testimony that we claim the foregoing we have hereunto set our hands at Milwaukee, in the county of Milwaukee and

20 State of Wisconsin.
